US00D963870S

(12) **United States Design Patent** (10) **Patent No.:** **US D963,870 S**
Careless et al. (45) **Date of Patent:** **** Sep. 13, 2022**

- (54) **MUSCLE STIMULATION DEVICE**
(71) Applicant: **Alura Inc.**, Houston, TX (US)
(72) Inventors: **Nathan Careless**, Cedar Park, TX (US); **Adam Prather**, Austin, TX (US); **Samuel Moon**, Austin, TX (US); **Lucas Wade**, Austin, TX (US); **Christy Sepulveda**, Austin, TX (US); **Scott Slade**, Round Rock, TX (US)
(73) Assignee: **Alura Inc.**, Houston, TX (US)
(**) Term: **15 Years**
(21) Appl. No.: **29/758,896**
(22) Filed: **Nov. 19, 2020**
(51) LOC (13) Cl. **24-01**
(52) U.S. Cl. **USPC .....** **D24/200**

(57) **CLAIM**

The ornamental design for a muscle stimulation device, as shown and described.

DESCRIPTION

FIG. 1 is a front perspective view illustrating our design for a muscle stimulation device.

FIG. 2 is a left side view thereof.

FIG. 3 is a rear view thereof.

FIG. 4 is a right side view thereof.

FIG. 5 is a front view thereof.

FIG. 6 is a top view thereof.

FIG. 7 is a bottom view thereof; and,

FIG. 8 is a rear perspective view thereof.

The broken lines in FIGS. 1, 3, 5, and 8 show portions of the article that form no part of the claimed design.

1 Claim, 8 Drawing Sheets
